UNITED STATES PATENT OFFICE.

FREDERICK DANIEL GROSS, RANDALL PORTER AKINS, AND JOHN WILLIAM BUCHER,
OF DENVER, COLORADO.

ROLLER-BEARING FOR TIRE AND TRUNNION TYPE MILLS.

1,401,536.

Specification of Letters Patent. Patented Dec. 27, 1921.

Application filed November 5, 1919. Serial No. 335,952.

To all whom it may concern:

Be it known that we, FREDERICK D. GROSS, RANDALL P. AKINS, and JOHN W. BUCHER, citizens of the United States, residents of 5 Denver, Colorado, have invented certain new and useful Improvements in Roller-Bearings for Tire and Trunnion Type Mills, of which the following is a specification.

Our invention relates to improvements in 10 bearings for cylindrical grinding mills, commonly known as tube mills, ball mills or rod mills.

In such mills as are used in the grinding of ores or other materials, it has been found 15 that a great excess of power is required, due mainly to the manner in which all types of present mills of which we are aware are carried in their bearings.

Our present invention aims to carry the 20 cylindrical mill at or near its center on a removable tire supported on rollers, which are carried in a casing entirely surrounding the mill and which rollers run on a track which forms an arc of a circle. Our invention aims 25 to support this track in a housing which acts as an oil reservoir for purposes of lubrication and to provide a lighter housing carried from this lower housing or oil reservoir around the balance of the rollers to keep the 30 same free from grit and dirt.

One end of the mill, preferably the feed 35 end, is supported by an ordinary trunnion bearing. This trunnion bearing is not intended to carry any appreciable portion of the mill load, but acts merely as a guide to balance the mill upon the main roller bearing. By so doing the other end of the mill, 40 namely the discharge end, is left easy of access so that the head can easily be removed, to enable new linings to be placed in the mill or enable the operator to easily inspect the interior of the mill at all times.

An embodiment of our invention is illustrated in the accompanying drawings in 45 which Figure 1 is a longitudinal section through the center of the mill showing the rollers in the form of segments of cones, the vertices of these cones all intersecting on the axis of the mill, one set converging toward the feed end and the other set toward the discharge end.

Fig. 2 is an enlarged detail of the removable tire, the conical rollers with their casting and the conical track.

55 Fig. 3 is a longitudinal section through a

modified form of the mill showing cylindrical rollers, with a cylindrical tire and a cylindrical track.

Fig. 4 is a partial end elevation and partial cross section of the mill shown in Fig. 3. 60

Referring by reference characters to these drawings the letter "a" designates the cylindrical shell of the mill, which is fastened at each of its ends to a flange ring "b" so designed as to fit into the counterbore of the 65 feed and discharge heads "c." The outer shell "a" is protected from abrasion of the material being ground by the lining "d" and the heads "c" are protected by the lining "e." The material to be crushed or ground is introduced into the mill by means of an ordinary 70 spiral scoop feeder "f" which delivers this material into the wearing sleeve "j" which has on its inner surface a spiral which forces the material to be ground into the 75 mill.

The trunnion "g" of the feed head "c" is protected from wear by this same wearing sleeve "j". The trunnion "g" is carried in a large ball and socket bearing, the letter 80 "h" indicating the ball and the letter "i" indicating the socket member. The discharge head is also protected from wear by means of the sleeve "k" which also acts as a spout to deliver the crushed or ground 85 material from the mill into a launder or other receptacle.

The conical or cylindrical rollers of the main bearings are indicated by the letter "l" and means for supporting these rollers 90 and keeping them in properly spaced position around the tire are indicated by the traveling rings "m" and "n", which are held apart by the spacers "x".

The removable tire is shown at "o" and it 95 is held in position by the following means:

Securely fastened to the shell "a" of the mill is a rigid ring section "p", over which the removable tire "o" is placed and then the ring section "q" is drawn into place 100 by means of the bolts "r", thus securely fastening the tire in position. Due to the fact that coating faces of the tire and ring sections "p" and "q" are inclined a wedging action is secured which effectually prevents 105 the tire "o" from slipping or crawling on the ring "p".

The stationary portion of the main bearing is a large substantial channel-shaped casting "t" which is lined with a removable 110

track "u" which may be of double frustro-conical shape as shown in Figs. 1 and 2. This housing "t" has sides "t'" which extend almost to the shell "a", thus forming a large and capacious oil reservoir.

Surmounting this housing "t" is a lighter and easily removable stationary housing "s" which completely encircles the balance of the rollers, keeping them free from grit and dirt, and acting as a means of returning any surplus oil which may adhere to the rollers or tire, back into the oil reservoir "t". Instead of using bearing rings with frustro-conical bearing surfaces, and a double set of anti-friction rollers as shown in Figs. 1 and 2, we may provide these parts with plain cylindrical surfaces as indicated at "o" and "u" respectively in Figs. 3 and 4 and use a single set of cylindrical anti-friction rollers "l'" spaced and guided by the side rings "m". The cylindrical mill may be rotated on its axis by any suitable means such for example as the spur gear "y" attached to the shell of the mill, as shown in Fig. 3.

Having thus described our invention, what we now claim is:—

1. In a cylindrical mill, a cylindrical mill shell having an annular tire, an annular 30 series of traveling rollers encircling said tire with means for holding them in spaced relation, and an arc-shaped support beneath said tire upon which the lowermost rollers of the series travel.
2. In a cylindrical mill, a cylindrical mill shell, having an annular tire, an annular 35 series of traveling rollers encircling said tire, a cage ring for holding said rollers in spaced relation, a stationary support beneath the shell having an arc-shaped por-

tion upon which the lowermost rollers travel, and a removable housing encircling the remainder of the rollers and having its ends connected with said support.

3. In a cylindrical mill, a mill shell, an 45 annular tire encircling the same, wedge means for removably holding said tire on said shell, a stationary support having an arc-shaped bearing surface beneath said tire, a roller cage ring encircling said tire, and 50 spaced rollers carried by said cage ring and arranged to travel between the tire and support as the shell rotates.

4. In a cylindrical mill, a mill shell, having a rigid ring section thereon with an inclined surface, a removable ring section having a reversely inclined surface with means for securing it to said rigid ring section, a tire having an inner surface reversely inclined to coact with the surfaces of said rigid and removable ring sections, an annular series of traveling rollers encircling said tire with means for holding them in spaced relation, and a stationary arc-shaped track beneath the shell upon which the lowermost 55 rollers bear.

5. In a cylindrical mill, a mill shell journaled upon a substantially horizontal axis, an anti-friction bearing at substantially the center of gravity of the shell for sustaining 70 the weight thereof, a trunnion at one end of the shell having a feed aperture, said shell having an unobstructed delivery opening at the opposite end.

In testimony whereof, we affix our signatures.

FREDERICK DANIEL GROSS.
RANDALL PORTER AKINS.
JOHN WILLIAM BUCHER.
